UNITED STATES PATENT OFFICE.

ADAMINA MARY MCQUHAE, OF TORONTO, ONTARIO, CANADA.

ATTACHMENT FOR ARM-BATHS.

1,105,365.

Specification of Letters Patent.

Patented July 28, 1914.

Application filed December 16, 1913. Serial No. 807,032.

To all whom it may concern:

Be it known that I, ADAMINA MARY MCQUHAE, of the city of Toronto, in the county of York, in the Province of Ontario, Canada, have invented certain new and useful Improvements in Attachments for Arm-Baths, of which the following is the specification.

My invention relates to improvements in arm baths and the object of the invention 10 is to devise a form of bath in which means are provided for preventing the bruising of the arm of the patient against the edge of the bath and it consists essentially of a receptacle designed to contain the necessary 15 solution and a suitable cushion inner edge of the receptacle as hereinafter more particularly described.

Figure 1, is a general perspective view of my device and showing its application. Fig. 20 2, is a vertical section through Fig. 1. Fig. 3, is a vertical section on line $x-y$ Fig. 2. Figs. 4 and 5 are enlarged perspective details of the bath, receptacle and cover. Fig. 6, is an enlarged perspective detail of the upper 25 end of the adjustable standard. Fig. 7, is a plan section on line $x'-y'$ Fig. 2.

In the drawings like letters of reference indicate corresponding parts in each figure.

A is a suitable base preferably supported 30 by the front end on casters A'.

B is a standard socket extending upwardly from one end of the base frame A.

B' is a stem extending downwardly into a socket standard B and provided at its upper 35 end with a right angular extension B² terminating in a supporting bracket B³ of any suitable form.

B⁴ is a clamping portion comprising two semi-circular portions together surrounding 40 the stem B' and provided with outwardly extending flanges B⁵ into which is threaded a clamping screw B⁶ for drawing the ends together and the semi-circular portion against the stem B'.

D is a tray supported by the bracket portion B² and suitably secured thereto. The tray D is provided at one end with a slot D' and a surrounding beaded rim D².

E is a receptacle designed to rest on the 50 tray D and preferably provided with an inclined end E'.

E² is a cover for the receptacle provided with a flanged semi-circular portion E³ forming an opening leading into the receptacle.

55

E⁴ is a handle for the cover.

E⁵ are hooked portions extending laterally from the sides of the receptacle E.

G is a pneumatic cushion provided with side straps G' having eyelets G² designed 60 to hook into the lateral hooks E⁵.

When the cushion G is inflated in the position shown it will be readily seen that the upper edge of the receptacle is protected so as not to hurt the arm of the patient when 65 held in such receptacle. In Fig. 1, I show the arm in position within the receptacle and indicated for the most part by dotted lines.

From this description it will be readily seen that my bath supported as shown may 70 be easily and readily elevated to any position according to the height of the patient's arm when either in a lying or sitting position and also may be swung if desired at any angle required over the bed so as to allow 75 of the patient changing his position and thus preventing over fatigue from the patient holding his arm continually in one position.

H is a discharge tap from which the fluid 80 may be drawn off from the receptacle when required.

H' and H² are supporting brackets designed to hold a suitable thermometer H³.

From this description it will be seen that 85 I have devised a very simple device in which means are provided whereby bruising or rubbing of the arm on the edge of the bath receptacle and a resulting soreness is prevented.

90

What I claim as my invention is.

In an arm bath, a bath receptacle having hooks extending laterally from one end thereof and a pneumatic cushion provided with side straps having eyelets designed to 95 extend over the edge of the bath and engage the hooks, as and for the purpose specified.

ADAMINA MARY MCQUHAE.
